UNITED STATES PATENT OFFICE.

WILBER R. DUNKEL, OF PANA, ILLINOIS, ASSIGNOR OF ONE-HALF TO CARTER R. SCROGGIN, OF HARRISTOWN, ILLINOIS.

STARTING DEVICE.

1,004,635.

Specification of Letters Patent.

Patented Oct. 3, 1911.

Application filed December 12, 1910. Serial No. 596,863.

To all whom it may concern:

Be it known that I, WILBER R. DUNKEL, a citizen of the United States, residing at Pana, in the county of Christian and State 5 of Illinois, have invented a new and useful Starting Device, of which the following is a specification.

This invention relates to internal combustion engines, and more especially to the 10 mechanical starting devices therefor; and the object of the same is to produce a device of this character by which an automobile can be cranked by the operator while sitting in his seat.

15 To this end the invention consists in the construction hereinafter more fully described and claimed, and as shown in the drawings wherein:

Figure 1 is a plan view and Fig. 2 is a 20 side elevation of the front portion of an automobile equipped with my improved device. Fig. 3 is an enlarged vertical section through the starter itself. Fig. 4 is a section on a line at right angles to the sectional line in Fig. 3. Fig. 5 is a sectional view 25 on the line 5—5 of Fig. 3. Fig. 6 is an enlarged detail sectional view on the line 6—6 of Fig. 4.

In the drawings, the letter A designates 30 broadly an automobile equipped with a gas engine whose crank shaft F projects through the forward end of its hood as usual, and as these engines are now constructed it is necessary to "crank" the engine in order to start it. This is accomplished by the operator who must descend 35 from his seat and go around in front of the machine and turn a hand crank, and then resume his seat. The object of the present 40 invention is to permit him to crank the engine without leaving his seat, and this is accomplished by the detailed construction which I will now describe.

Keyed upon the main shaft F is a wheel 45 5 having ratchet teeth 6 around its periphery and conical ends 7 as best seen in Fig. 3, which ends rotate within bearings 8 formed within a drum, the latter consisting of a cup-shaped body 9 carrying one bearing 8 and a plate 10 threaded as at 11 into mouth of the cup and carrying the other bearing. Both the bottom of the body 9 and plate 10 have central openings 12 for the shaft F at either side of the wheel 5. 55 The drum is shown in Figs. 1 and 2 as

standing in front and outside of the hood, but it may be arranged within the same without departing from the spirit of my invention.

The numeral 13 designates a cable wound 60 around a groove 14 in the wall of the drum, extending thence over a pulley 22, and leading backward to manipulating means broadly designated by the numeral 15 but herein shown as consisting of a lever pivoted at 16 within the framework of the automobile and connected at 17 with the cable 13. Wound reversely around the drum in another groove 140 is a second cable 130 which leads to a retracting device here broadly 70 designated by the numeral 120 and shown as a coiled spring of which one end is attached to the cable and the other to some fixed part of the automobile. Thus it will be seen that when the manipulating means is operated 75 by the driver the drum is turned against the tension of the retracting means, and when the driver's pressure is removed the retracting means restores the drum to its 80 original position.

Within the wall of the drum is cast a lug 30 pierced with a threaded hole 31, and through the bottom of the drum passes loosely a screw having a smooth shank 32 and a threaded portion 33 adapted to engage the threaded hole 31, and having beyond its threaded portion 33 a reduced tip 34 also smooth. The latter is intended to enter one of a series of holes 35 formed through the plate 10 which closes the mouth 90 of the drum, and by this means it will be clear that when the screw is loosened and withdrawn slightly its tip is removed from one of the holes 35 and the plate can then be turned in its thread 11 to adjust its 95 bearing 8 tighter or looser upon the cone 7 of the wheel 5.

Pivotedly mounted on the smooth portion 33 of the screw is a pawl 40 whose tip is adapted to engage the teeth 6 of the wheel 5, 100 and 41 is a spring secured within the drum and bearing said tip normally into engagement therewith. Laterally from said pawl projects a pin 42 passing loosely through a radial slot 43 in the bottom of the drum and 105 adapted to make contact with a cam 44 secured by any suitable means as a bracket 45 to some fixed portion of the automobile as best seen in Fig. 3. The obvious purpose of this cam is to disengage the pawl from 110

the ratchet wheel at a proper moment. Thus when the operator moves the manipulating means he rotates the drum and gives a partial rotation to the main shaft F, and on the 5 return movement of the drum the pin 42 rides up the cam and lifts the tip of the pawl 40 out of engagement with the teeth 6. The fact that the latter are ratchet instead of ordinary teeth permits the shaft to rotate 10 faster than the drum in case the engine should start quickly. As soon as the operator removes his foot from the pedal or otherwise releases tension upon the operating means, the retracting means restores the parts to 15 their normal positions, as will be understood. It seems hardly necessary to go further into the details of the operation of this device, more than to add that in case of back-fire the reversely turning ratchet wheel would 20 carry the pawl and drum with it only far enough to cause the pin on the former to ride up the cam and disengage its tip from the ratchet teeth.

What is claimed as new is:

25 1. In a starting device for gas engines, the combination with a ratchet wheel fixed on the engine shaft and having conical ends; of a drum comprising a cup-shaped body having in its bottom a hole for said shaft 30 and a bearing face adapted to rest on one of said ends, and a plate threaded into the mouth of the cup and having a central hole for said shaft and a bearing face adapted to rest on the other of said ends, the plate 35 having a series of perforations through it, a lug cast within the rim of the body and having a threaded hole, a screw passing through the bottom of said body and screwing through said hole and having a reduced tip 40 engaging one of the perforations in said plate to hold the latter in adjusted position, a pawl pivoted on the body of the screw with its tip directed toward said teeth, a spring pressing the tip toward the teeth, 45 manipulating means for directing the rotation of the drum in one direction, and retracting means for normally rotating it in the other direction.

2. In a starting device for gas engines, 50 the combination with a ratchet wheel fixed on the engine shaft and having conical ends; of a drum comprising a cup-shaped body

having a hole in its bottom for said shaft and a bearing face adapted to rest on one of said ends, and a plate threaded into the mouth of the cup and having a central hole for said shaft and a bearing face adapted to rest on the other of said ends, a lug cast within the rim of the body and having a threaded hole, a screw passing through the bottom of said body and screwing through said hole and having a reduced tip 55 engaging said plate to hold the latter in adjusted position, a pawl pivoted on the body of the screw with its tip directed toward said teeth, manipulating means for directing the rotation of the drum in one direction, retracting means for normally rotating it in the other direction, and means for disengaging the tip of the pawl from said teeth when 60 the drum is retracted.

3. In a starting device for gas engines, the combination with a ratchet wheel fixed on the engine shaft and having conical ends; of a drum comprising a cup-shaped body 75 having a hole in its bottom for said shaft and a bearing face adapted to rest on one of said ends, and a plate threaded into the mouth of the cup and having a central hole for said shaft and a bearing face adapted to rest on the other of said ends, a lug within the body and having a threaded hole, a screw passing through the bottom of said body and screwing through said hole and having a reduced tip 80 engaging said plate to hold the latter in adjusted position, a pawl pivoted on the body of the screw with its tip directed toward said teeth, manipulating means for directing the rotation of the drum in one direction, retracting means for normally rotating it in the other direction, the bottom of said drum being provided with a radial slot, a pin on the pawl projecting through said slot, and a fixed cam outside 85 the drum upon which said pin rides as the 90 drum returns to its retracted position.

In testimony that I claim the foregoing as my own, I have hereto affixed my signature in the presence of two witnesses.

WILBER R. DUNKEL.
